UNITED STATES PATENT OFFICE.

ALBERT M. BURRITT AND ANGELO C. BURRITT, OF WATERBURY, CONNECTICUT, ASSIGNOR TO THE A. BURRITT HARDWARE COMPANY, OF SAME PLACE.

FIRE-EXTINGUISHER.

SPECIFICATION forming part of Letters Patent No. 254,271, dated February 28, 1882.

Application filed December 24, 1881. (No model.)

To all whom it may concern:

Be it known that we, ALBERT M. BURRITT and ANGELO C. BURRITT, of Waterbury, in the county of New Haven and State of Connecticut, have invented a new Improvement in Fire-Extinguishers; and we do hereby declare the following, when taken in connection with the accompanying drawings and the letters of reference marked thereon, to be a full, clear, and exact description of the same, and which said drawings constitute part of this specification, and represent, in—

Figure 1, a longitudinal section of the distributor, showing the plug in the water-way; Fig. 2, the ring detached; Fig. 3, the plug detached.

In fire-extinguishers which consist in a pipe extending through the apartment to be protected, with perforated distributors at different points, a plug is usually attached in the water-way by a fusible metal, or a fusible plug is secured in the water-way, so that when the heat in the apartment rises to a certain degree the plug will be liberated and permit the water to flow through the distributor to extinguish the fire. A plug made of fusible metal is the best stop for the water, but it is difficult to secure such a plug in the water-way; hence a hard-metal plug is more generally employed, soldered to the walls of the water-way; but this hard plug is not so certain of being liberated by the heat as the soft-metal plug, but is more readily secured to the walls.

The object of this invention is to produce a soft or fusible metal plug with a hard-metal surface around its circumference, by means of which it may be soldered into the water-way, and in such a plug the invention consists.

We first prepare a ring, A, from hard metal, as brass, of a diameter corresponding to the internal diameter of the water-way B; then into this ring A we secure a plug, C, of fusible material, such as usually employed for such plugs; then the plug C, with its hard-metal edge A, is introduced into the water-way, and there secured by solder in the usual manner for securing hard-metal plugs, as seen in Fig. 1.

By this construction all liability of injuring the soft-metal plug in soldering it into the water-way is avoided, because the soldering is done upon the surface of the hard metal, and all the benefits of a fusible plug, combined with those of a hard-metal plug, are attained.

I claim—
The herein-described improvement in fire-extinguishers, consisting of the plug composed of the hard-metal ring A and the fusible part C, filling said ring, and the plug secured in the water-way by means of said hard-metal ring, substantially as described.

ALBERT M. BURRITT.
A. C. BURRITT.
